SPECTACLE DISPLAY STAND

Anthony De Witt Glover, Austin, Tex.

Application March 13, 1958, Serial No. 50,023

Term of patent 14 years

(Cl. D80—9)

Fig. 3.

Fig. 4.

Fig. 1 is a front elevational view of a spectacle display stand embodying the design;

Fig. 2 is a fragmentary perspective view thereof taken on line 2—2 of Fig. 1 looking in the direction of the arrows;

Fig. 3 is a top plan view thereof; and

Fig. 4 is a fragmentary end perspective view thereof.

The dotted line showing of spectacles in Fig. 2 is for illustrative purposes only.

In the drawing, the dominant features of the design are shown in full lines, the spectacle clips being omitted from Figs. 3 and 4 for convenience of illustration.

I claim:

The ornamental design for a spectacle display stand, substantially as shown and described.
